Primary Examiner — Jennifer Rivard(74) *Attorney, Agent, or Firm* — Kevin C. Johnson; Joanne N. Pappas(57) **CLAIM**

The ornamental design for a razor component, as shown and described.

DESCRIPTION

FIG. 1 is a front perspective view of a design of a razor component of the present invention;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The evenly spaced broken lines illustrate portions of the razor component and form no part of the claimed design. The dash-dot-dash broken lines illustrate the bounds of the claim and form no part of the claimed design.

1 Claim, 6 Drawing Sheets(56)
